UNITED STATES PATENT OFFICE.

HORACE WYMAN AND ALBERT A. GORDON, JR., OF WORCESTER, MASSACHUSETTS, ASSIGNORS TO CROMPTON & KNOWLES LOOM WORKS, OF WORCESTER, MASSACHUSETTS, A CORPORATION OF MASSACHUSETTS.

MULTIPLIER MECHANISM FOR LOOMS.

SPECIFICATION forming part of Letters Patent No. 700,999, dated May 27, 1902.

Application filed June 10, 1901. Serial No. 62,844. (No model.)

To all whom it may concern:

Be it known that we, HORACE WYMAN and ALBERT A. GORDON, Jr., citizens of the United States, residing at Worcester, in the county of Worcester and State of Massachusetts, have jointly invented certain new and useful Improvements in Multiplier Mechanisms for Looms, of which the following is a specification.

10 Our invention relates to looms for weaving textile fabrics, and particularly to that class of looms in which, in connection with the drop-box pattern-chain mechanism, auxiliary or multiplier pattern-chain mechanisms are used.

15 The object of our invention is to reduce the length of the drop-box pattern-chain and provide means for automatically reversing said chain and means for repeating a certain portion of said chain and also means for multiplying a given pick.

20 Our invention consists in certain novel features of construction of our pattern-chain mechanisms, as will be hereinafter fully described.

25 We have only shown in the drawings sufficient parts of a loom with our improvements applied thereto to enable those skilled in the art to which our invention belongs to understand the construction and operation thereof.

30 Referring to the drawings, Figure 1 is a plan view of pattern-chain mechanisms embodying our improvements. Fig. 2 is a side view of the parts shown in Fig. 1, taken at a point indicated by line 2 2, Fig. 1, looking in the direction of arrow *a*, same figure; and Fig. 3 is a section through the parts shown in Fig. 1, taken at a point indicated by line 3 3, same figure.

35 A framework (not shown) is attached to the loom side (not shown) and has bearings for the several shafts and studs. (Shown in the drawings.)

40 To the upright rod 1 (shown in Fig. 2) is communicated from a driven part of the loom (not shown) a regular up-and-down motion. The upper end of said rod 1 is adjustably connected by a bolt 2, having a nut 2' thereon, with a slotted portion 3' of the plate 3, which

has a hub 3", mounted to rock on a stud 4. 50 In slots 3'" in the plate 3 are adjustably secured studs 5 and 6. A stud 7 is also secured in the plate 3. On the stud 5 is pivotally mounted the pull-pawl 8, and on the stud 6 the push-pawl 9, and on the stud 7 the pull-paws 10 and 11.

A shaft 12 rotates in bearings on the frame, (not shown,) and fast on said shaft 12 is the drop-box pattern-chain cylinder 13, carrying a chain 14, made up of bars, carrying rolls 60 and tubes and connected by links in the ordinary way. One drop-box indicator-lever 13' is shown in Fig. 1 extending over the chain 14 in the ordinary way. Two ratchet-wheels 15 and 16 are fast on the shaft 12, with their 65 teeth extending in opposite directions (as shown in Fig. 3) and adapted to be engaged and operated at the proper time by the pawls 8 and 9 to turn the pattern-chain cylinder 13 and the pattern-chain 14 forward or back, as 70 desired.

A shaft 17 is fixed in bearings on the frame (not shown) and has loosely mounted thereon the auxiliary-pattern-chain cylinder 18, carrying the pattern-chain 19, made up of bars connected by links, some of said links 19' being made higher, as shown in Fig. 2, to act as pattern-surfaces. A ratchet-wheel 18' is connected to or made integral with the auxiliary pattern-chain cylinder 18 and is operated by a 75 projection 11' on the pull-pawl 11. (See Fig. 2.)

A shaft 20 rotates in bearings on the frame (not shown) and has loosely mounted thereon a multiplier-pattern-chain cylinder 21, (see 85 Fig. 1,) carrying the multiplier pattern-chain 22 of similar construction to the chain 19, above referred to. A ratchet-wheel 23 is fast on the shaft 20 and is adapted to be engaged by a pull-pawl, hereinafter described. A 90 ratchet-wheel 23' is made integral with the pattern-chain cylinder 21 and is operated by the pull-pawl 10 to turn the cylinder 21. On the opposite end of the shaft 20 is fast the stopping or arresting device 24. (Shown in Figs. 1 and 3 at the right.) Said device 24 consists in this instance of two adjacent disks or cams, which have recesses 24' in their peripheries

at regular intervals, the recesses being arranged alternately on the two cams, so that they will not come opposite each other; but a recess in one cam will come opposite the non-recessed portion on the other cam, as shown in Figs. 1 and 3.

On a shaft 25 are pivotally supported two controlling-levers 26 and 27. Each lever has an arm 26' and 27', with an upward projection 26" and 27" thereon, which extends under the arresting device 24 and is adapted to engage the recessed portions 24' in said device, as shown in Fig. 3. The opposite ends 26''' and 27''' of the controlling-levers 26 and 27 are curved to extend over the ratchet-wheels 15 and 16 and to support the pawls 8 and 9 by means of pins 8' and 9' extending out from said pawls, as shown in Fig. 3.

The forked end 29' of a connector-lever 29 is supported on the shaft 25 and secured thereto by the pin 28. (See Fig. 1.) The cross-bar 29" of the lever 29 extends over and rests on the levers 26 and 27, as shown in Figs. 1 and 3, and the extended end of the lever 29 has attached thereto a connector 30, which is connected at its lower end with mechanism for calling the multiplier into action, (not shown,) but which may be of any ordinary construction and operation.

On the stud 17 is loosely mounted a change-lever 32, with one end 32' extending over the pattern-chain 14 and held in contact therewith by a spring 33 and the other end 32" bent at its extreme end, as shown by dotted lines in Fig. 1, and extending under and supporting the pull-pawl 10, as shown in Fig. 2.

On the pull-pawl 10, near its free end, is a hub-like extension through which extends the pin 35. On the pin 35 is mounted the hub 36' of the double or forked pawl, having the pull-pawl end 36" extending over the ratchet 23 (see Fig. 2) and the plain end 36''' extending over and resting on the chain 22. (See dotted lines, Fig. 2.) An extension 36''' on the end 36" extends over and rests on the end of the pull-pawl 10, (see Fig. 1,) so that when the pull-pawl 10 is raised the forked pawl will be raised.

On the shaft 17 is loosely mounted the lever 40, having one end 40' extending over the pattern-chain 14 and held in engagement therewith by the spring 41 and having its opposite end 40" curved upwardly and bent to extend under and support the pull-pawl 11, as shown in Fig. 2.

On the shaft 25 is fast a multiplier arm 43, which engages with the pattern-chain 14 when the connector-lever 29 is released by the connector 30 to allow the shaft 25 to rotate.

We will now describe the operation of the pattern mechanisms shown in the drawings.

When the multiplier pattern-chain 22 is called into action, the connector 30 being released to allow the connector-lever 29 to be raised and with it the bar 29'', extending over controlling-levers 26 and 27, thus releasing said levers, the lever 26 will in this instance

move on its pivotal support, and the extension 26'' thereon will extend into one of the recessed portions 24' in the arresting device 24. The lever 27 will be prevented from moving by reason of the extension 27'' thereon engaging the non-recessed portion on the arresting device 24. The rocking of the lever 26 on its pivotal support will lower the curved end 26''' of said lever and allow the pull-pawl 8 to engage the ratchet-wheel 15. An upward stroke of the rod 1 will rock the plate 3 and communicate movement to the pawl 8 and cause it to rotate the ratchet-wheel 15 the distance of one tooth. At the same time the drop-box pattern-chain cylinder 13 will be rotated and the chain 14 moved one bar to carry the roll 14', Fig. 2, from under the end 32' of the change-lever 32. This allows the end 32' to drop, drawn down by the spring 33, and raises the opposite end 32" of said lever 32, which engages the pull-pawl 10 and raises said pawl out of engagement with the ratchet-wheel 23'. The raising of the pawl 10 will simultaneously, through the extension 36''', extending over the pawl 10, raise the pawl 36'' out of engagement with the ratchet-wheel 23 and the end 36''' of the pawl out of engagement with the pattern-chain surface 22, so that in the continued movement of the rod 1 and the rocking plate 3 the pawl 10 and pawl 36'' will be held out of engagement with the ratchet-wheels 23 and 23', and the pull-pawl 8 will continue to revolve the ratchet-wheel 15 and the pattern-chain 14 a bar at a time until, if a complete revolution of the chain is desired, the roll 14' is again brought under the lever 32 to raise said lever, and at the same time lower the pawl 10 and the double or forked pawl to allow the pawl 36'' to engage and move the ratchet-wheel 23 and the pawl 10 to move the ratchet-wheel 23' by the continued motion of the rod 1 and rocking plate 3. The rotation of the ratchet-wheel 23 moves the arresting device 24 to bring a non-recessed portion over the extension 26'' on the lever 27, thus moving the lever 26 on its pivotal support and through its end 26''' raising the pawl 8 out of engagement with the ratchet-wheel 15. At the same time the lever 27 will rock on its pivotal support and the end 27''' will be lowered to allow the pull-pawl 9 to engage with its ratchet-wheel 16 and rotate said ratchet-wheel and the pattern-chain cylinder 13 in the opposite direction, moving the roll 14' out from under the lever 32 and allowing said lever to be moved by the spring 33 to raise the pawl 10 and forked pawl out of engagement with their ratchet-wheels 23 and 23', as above described. The reverse motion of the pattern-chain 14 will continue until the roll 14' again comes under the end 32' of the lever 32, when the operation above described is repeated and the chain 14 will again be moved in a forward direction—that is to say, an indicator, as roll 14', carried on the pat-

tern-chain, will when brought under lever 32 cause the pattern-chain itself to reverse its movement, whichever way the chain may be moving at the time the roll is moved under the lever.

Instead of making a complete revolution of the pattern-chain before reversing its movement, as above described, another roll 14' may be placed on the chain at such a distance from the first-mentioned roll 14' as will contain a suitable number of bars for a pattern to be woven first forward and then in a reversed manner as long as desired. The remaining portion of the pattern-chain not included between these two rolls 14', may carry another pattern, which can be brought into operative position under the indicator-lever 13', as hereinafter described.

We will now describe the operation of the pattern-chain mechanism when it is desired to repeat a given section of the pattern-chain 14 instead of reversing it, as above described.

It will be understood that when the forked pawl engages the ratchet-wheel 23 to turn the arresting device 24, as above described, the pawl 10 will at the same time engage the ratchet-wheel 23' and turn the multiplier-pattern-chain cylinder 21. The continued revolution of the multiplier-pattern-chain cylinder 21 will bring the high link 22' on the chain 22 under the end 36" of the forked pawl to raise said end 36" and at the same time raise the pawl end 36" out of engagement with the ratchet-wheel 23, leaving said ratchet-wheel and the shaft 20 and the arresting device 24 at rest. The main box-pattern chain 14 will continue in the same direction as before—that is, if the pawl 8 is down and operating the pattern-chain cylinder 13 it will continue down, and if the pawl 9 is down and operating the pattern-chain cylinder 13 in the opposite direction it will continue down, for the rotation of the arresting device 24 to effect the exchange of pawls 8 and 9, as above described, will not take place, and therefore a given section of the pattern-chain 14 will be repeated instead of the chain being reversed.

We will now describe the operation of the mechanism in case it is desired to multiply a given pick.

In the revolution of the pattern-chain 14, in case it has additional rolls, as 42, to be brought under the lever 40, when a roll 42 (see Fig. 2) is brought under the end 40' of the lever 40 it will raise said lever 40 and lower the end 40", extending under the pawl 11, to allow the extension 11' on the pawl 11 to engage with the ratchet-wheel 18', connected with the auxiliary-pattern-chain cylinder 18, and turn said ratchet-wheel and cylinder and move the chain 19 thereon until a high link 19' on said chain 19 is brought under the multiplying-arm 43, which arm through the releasing of the connector 30 and the movement of the lever 29 and the rotation of the shaft 25 is allowed to engage the pattern-chain 19. The passing

of a link 19' under the arm 43 raises said arm and rotates the shaft 25 in the direction of arrow e, Fig. 2, to move the lever 29 and cause 70 the cross-bar 29" thereof to bear on the controlling-levers 26 and 27 to move said levers on their pivotal supports and raise the ends 26" and 27" of said levers to cause them to engage the pins 8' and 9' on the pawls 8 and 9 and raise said pawls out of engagement with their respective ratchet-wheels 15 and 16. The multiplication will continue as long as there is an unbroken succession of the high links 19' on the chain 19, as shown in Fig. 2; 80 but as soon as a low link comes under the arm 43 the shaft 25 will be rotated in an opposite direction, when the connector 30 is released and the levers 26 and 27, through the movement of the cross-bar 29", will be released and 85 allowed to move to allow one of the pawls 8 or 9 to engage with its ratchet-wheel, according to the position of the arresting device 24.

It will be seen that with the above-mentioned improvement in pattern-chain mechanisms a pattern can be woven back and forth as long as desired, governed as to its back-and-forth movements by its own self-contained indicators, and also multiply given picks in either direction of the moving patterns, and 95 afterward a new pattern can be brought into operative position, which can also be woven back and forth and given picks multiplied, as in the first-mentioned pattern.

It will be understood that the details of construction of our pattern-chain mechanism may be varied, if desired.

Having thus described our invention, what we claim as new, and desire to secure by Letters Patent, is—

1. In a loom, a main pattern-surface with indicators, a change-lever adapted to be moved by said indicators, and pawls adapted to move the pattern-surface in either direction, and means between said change-lever and said pawls to reverse the direction of movement of said main pattern-surface, of a multiplier pattern-surface carrying indicators to prevent the indication of said change-lever, and cause said main pattern-surface to 110 continue its movement in the same direction, substantially as shown and described.

2. In a loom, a main pattern-surface, a pair of reversely-acting ratchet-wheels, on the shaft of said main pattern-surface, and coöperating pawls to move said ratchet-wheels, of a main change-lever moved by indications on said main pattern-surface, and intermediate connections between said lever and said pawls, to put either pawl into operative position with 125 its respective ratchet-wheel, substantially as shown and described.

3. In a loom, the combination with a main pattern-surface, a pair of reversely-acting ratchet-wheels on its shaft, and coöperating 130 pawls to move said ratchet-wheels, and a main change-lever moved by indications on said main pattern-surface, and intermediate connections between said lever and said pawls,

to put either pawl into operative position with its respective ratchet-wheel, of a multiplier pattern-surface, and intermediate connections between said two pattern-surfaces, by 5 means of which the main pattern-surface is caused to stop at predetermined intervals, and a multiplier controlling-lever, and intermediate connections between said multiplier controlling-lever and said pawls, whereby 10 said lever will put into an inoperative position either pawl, which may be at the time in operative position, substantially as shown and described.

4. In a loom, the combination of a main pattern-surface, means for moving said main pattern-surface either forward or backward, an auxiliary pattern-surface, means under control of the main pattern-surface for determining the operation of the auxiliary pattern-surface, controlling devices for controlling the movement of the main pattern-surface, and means intermediate the auxiliary mechanism and said devices for determining the operative or inoperative action of the main pattern-surface.

25 5. In a loom, the combination of a main pattern-surface, means for moving said main pattern-surface either forward or backward, controlling-levers for controlling the operation

of the main-pattern-surface-actuating means, 30 an auxiliary pattern-surface, means under control of the main pattern-surface for operating said auxiliary pattern-surface, a multiplying-arm operable from said auxiliary pattern-surface, a connector-lever in operative 35 relation to said multiplying-arm, and means connected to said lever to move both controlling-levers to render inoperative the main-pattern-surface-actuating means.

6. In a loom, the combination of a main pattern-surface, means for moving it either backward or forward step by step to the extent desired, controlling-levers for determining the movements of the main pattern-surface, a multiplier pattern-surface controlled in its 40 operation from the main pattern-surface to determine the position of each of the controlling-levers, an auxiliary pattern-surface also controlled in its operation from the main pattern-surface, and means operable therefrom 45 to act upon both controlling-levers to render inoperative the main-pattern-surface-actuating means.
